UNITED STATES PATENT OFFICE

170,310

SOFT DRINK DISPENSING MACHINE

Paul Destun, St. Thomas, Ontario, Canada

Application February 20, 1953, Serial No. 23,714

Term of patent 3½ years

(Cl. D2—3)

To all whom it may concern:

Be it known that I, Paul Destun, a subject of the Queen of Great Britain, residing at St. Thomas, Ontario, Canada, have invented a new, original, and ornamental Design for a Soft Drink Dispensing Machine, of which the following is a specification, reference being had to the accompanying drawings, forming a part hereof.

In the drawings:

Fig. 1 is a front perspective view of a soft drink dispensing machine embodying my new design; the other side, not shown, is like the side shown.

Fig. 2 is a front elevational view, and

Fig. 3 is a top plan view thereof.

I claim:

The ornamental design for a soft drink dispensing machine, as shown and described.

PAUL DESTUN.
